UNITED STATES PATENT OFFICE

JOHN W. CARLSON, OF CHICAGO, ILLINOIS

DESIGN FOR A GOLF STROKE COUNTER

Application filed March 11, 1931. Serial No. 39,028. Term of patent 3½ years.

To all whom it may concern:

Be it known that I, JOHN W. CARLSON, a citizen of the United States, residing at Chicago, in the county of Cook and State of Illinois, have invented a new, original, and ornamental Design for a Golf Stroke Counter, of which the following is a specification, reference being had to the accompanying drawings, forming part thereof.

Figure 1 is a perspective view of the counter illustrating my new design;

Figure 2 is a plan view of the counter on an enlarged scale; and

Figure 3 is an elevation thereof on an enlarged scale.

I claim:

The ornamental design for a golf stroke counter as shown.

In witness whereof, I hereunto subscribe my name this 7th day of March, 1931.

JOHN W. CARLSON.
